UNITED STATES PATENT OFFICE

2,458,335

ATTACHING PANEL FOR KEY CASES

Douglas J. Broughton, Springfield, Mass., assignor
to Buxton, Incorporated, Springfield, Mass., a
corporation of Massachusetts

Application November 8, 1946, Serial No. 708,647

2 Claims. (Cl. 150—40)

1

This invention relates to an improvement in key cases and more particularly to an improved manner of securing the key holding mechanism to the case.

The principal object of the invention is to provide a one piece panel structure to which the key holding mechanism may be secured in a manner to conceal all of the mechanism except that essentially available for the attachment and detachment of the keys and which may at the same time be arranged to form a pocket for the carrying of small cards, papers and the like.

In the accompanying drawings which show one illustrative embodiment of the invention,

Fig. 1 is a front view of a key case in open position;

Fig. 2 is a view of the front side of a blank from which the attaching panel of the invention may be formed;

Fig. 3 is a view of the rear side of the panel with the side members folded into position;

Fig. 4 is a view similar to Fig. 3 but with the bottom member folded and stitched in position; and

Fig. 5 is a fragmentary sectional view substantially on line 5—5 of Fig. 1.

Referring to the drawings, the body of the case is shown as comprising a center portion 1 to which the attaching panel of the present invention, generally indicated at 2, is secured as later described. Extending from the sides of center portion 1 are side flaps 3 and 4 adapted to be folded in overlapping relation over panel 2 to close the case in a conventional manner. The flaps 3 and 4 are respectively provided with conventional snap fastener elements 5 and 6 by which the case may be releasably held closed.

As shown in Fig. 2 the attaching panel consists of a front member 7, side flaps 8, extending sidewise from the upper portion of the front member 7, and a pocket forming flap 9 extending from the bottom of the front member.

The side flaps 8 are connected to the front member along parallel fold lines indicated at 10, and have portions 11 which extend above the upper edge of the front member. The portions 11 are notched, outwardly of fold lines 10, as indicated at 12, a distance approximately equal to the thickness of the key holder plate to be secured to the finished panel.

The side flaps 8 have a width at the bottom substantially equal to one half the width of the front member 7, but their free side edges 13 flare outwardly an amount substantially equal to the transverse depth of the notches 12. When the

2

side flaps are folded against the back of front member 7 and the edges 13 are brought into abutting relation as in Fig. 3, this flaring of the edges brings the notched edges of extensions 11 into general alignment with the folded edges 10. The lower portion of the side flaps 8 are cemented to the back of member 7 up as far as a transverse line 14 which is spaced from the upper edge 15 of section 7 a distance substantially equal to the height of the plate of the key holder mechanism later described.

The flap 9 is next folded onto the rear face of member 7 and in overlapping relation on the lower portions of the flaps 8 as shown in Fig. 4. The side and bottom edges of flap 9 are then stitched as at 16 to the edge of the front member, forming a pocket opening upwardly at 17.

The upper edge of the center part 1 of the case is formed with a short extension 18, see Fig. 5, which is folded inwardly of the case. The extending portions 11 of the panel are stitched, as at 19, to the extension 18.

The keyholder mechanism, generally indicated at 20, includes a plate portion 21 having a slotted cylinder 22 along its upper edge, in the slots of which key hanger loops 23 are releasably secured. The specific structure of the key holder mechanism is not a feature of the present invention. The form shown here for purpose of illustration is generally similar to that disclosed and described in the prior patent to Boden 2,114,122, issued April 12, 1938.

The plate 21 is inserted, as shown in Figs. 1 and 5 in the pocket formed between the un cemented portions of member 7 and flaps 8 above the line 14 with the cylinder 22 extending over the edge 15 of member 7. The mechanism 20 is then secured in place by means of rivets 24 extending through member 7 and flaps 8 and the plate 21 inserted therebetween.

Preferably the member 7 and flaps 8 of the blank from which the panel is formed are provided, before the blank is folded up, with rivet securing openings 25 positioned to register with preformed rivet openings in the plate 21.

As will be apparent from the above description and the accompanying drawings, the attaching panel of the present invention conceals the plate 21, and all exposed parts of the panel, both front and back, present the grain or finished surface of the leather. Furthermore the plate of the key holder mechanism is held in proper position by the folds 10 and the edge 15 during the positioning and upsetting of the rivets 24, greatly facilitating the operation of assembly. The slight flar-

ing of the side flaps 8 provides the necessary fullness to accommodate the plate between the walls while permitting the leather below the plate to adjust itself smoothly and without wrinkles. All of these advantages are obtained in a one piece construction, which is much more easily and economically made up than where several individual pieces have to be separately cut and assembled.

I claim:

1. In a key case, a panel by which a key holding mechanism, having a plate member provided with key connecting members along its upper edge, is attached to the case which comprises, a piece of flexible material having a front member, flap members extending from the sides thereof and folded rearwardly onto the rear face of said front member, the lower portions of said flap members being secured to the adjacent face of the front member, the upper portions being free of attachment to the front member to provide a pocket in which the plate holding member of the key holding mechanism is positioned with the key connecting members exposed above and along the upper edge of the front member, a bottom flap extending from the lower edge of the front member and folded rearwardly upon the lower portions of said flap members, the side edges of said bottom flap being secured to the side edges of the front member to form an upwardly opening pocket on the rear face of the panel, means securing the key holding mechanism in the first named pocket and means connecting the upper edges of said side flap members to the keycase.

2. In a key case, a panel by which a key holding mechanism, having a plate member provided with key connecting members along its upper edge, is attached to the case which comprises, a piece of flexible material having a front member, flap

members extending from the sides thereof, said flap members being slightly wider at the top than at the bottom, said flap members being folded rearwardly onto the rear face of said front member with their free side edges abutting each other, the lower portions of said flap members being secured to the adjacent face of the front member, the upper portions being free of attachment to the front member to provide a pocket in which the plate holding member of the keyholding mechanism is positioned with the key connecting members exposed above and along the upper edge of the front member, the upper edges of said flap members extending upwardly behind the key connecting members, a bottom flap extending from the lower edge of the front member and folded rearwardly upon the lower portions of said flap members, the side edges of said bottom flap being secured to the side edges of the front member to form an upwardly opening pocket on the rear face of the panel, means securing the key holding mechanism in the first named pocket and means connecting the upper edges of said side flap members to the keycase.
